UNITED STATES PATENT OFFICE.

JOSHUA LINCOLN MORRIS, OF CHICAGO, ILLINOIS.

SALES-REGISTER.

1,316,103.

Specification of Letters Patent. Patented Sept. 16, 1919.

Application filed January 18, 1918. Serial No. 212,513.

To all whom it may concern:

Be it known that I, JOSHUA LINCOLN MORRIS, a citizen of the United States, and a resident of Chicago, in the county of Cook and State of Illinois, have invented certain new and useful Improvements in Sales-Registers; and I do hereby declare that the following is a full, clear, and exact description thereof, reference being had to the accompanying drawings, and to the letters of reference marked thereon, which form a part of this specification.

This invention relates to improvements in sales registers and consists of the matters hereinafter described and more particularly pointed out in the appended claims.

The object of the invention is to provide what may be called a pocket sales register, that is to say, a sales register which may be carried in the pocket and be at hand in the possession of the salesman in the same manner and with the same ease of disposal about his clothing as a common memorandum or manifold sales book.

In the case of nearly every business, one situation is confronted, which is not met either by cash registers, autographic registers, or by sales books. The following examples illustrate such situation.

In the case of counter sales, where at present a sales slip book is used, it is possible for the salesman to change or alter the amounts entered on his loose leaf record slip as compared to those on the check or receipt slip to be handed to the purchaser, and by conspiring with others in the employ of the shop, to give the purchaser an acceptable receipt for the cash paid, part of which may be pocketed without detection and only the remaining part returned to the cashier.

Again, in the case of outside salesmen, as for example, salesmen at gasolene service stations, where the sales are made quickly and amounts paid are hurriedly given to the salesmen without the purchaser waiting for a cash receipt for the amount paid, it is possible for great confusion and loss to occur in the amounts returned by the salesmen, either on account of dishonesty on the part of the salesmen or on account of the hurry and confusion of the sales themselves and the impossibility of making out the necessary sales and record slips.

Other examples will readily occur to those

familiar with the matter, to illustrate the inadequacy of present devices to fully meet the situation.

Another object of the present invention is to provide a pocket sales register which may be used either on the counter or on the street, in the use of which it is absolutely essential for the salesman to make a record of every sale made and to give the purchaser a receipt check, and to do this without any possibility of his altering or changing the record.

The many advantages of the invention will appear as I proceed with my specification.

In the drawings:—

Figure 1 is a view representing in perspective, my improved pocket sales register.

Fig. 2 is a view representing a longitudinal central section through the register in a plane indicated by the line 2—2 of Fig. 1.

Fig. 3 is a view representing, on an enlarged scale, a transverse section through the device in a plane indicated by the line 3—3 of Fig. 2.

Fig. 4 is a view representing a transverse section through the device in a plane indicated by the line 4—4 of Fig. 2.

Fig. 5 is a partial, longitudinal section through the device in a plane indicated by the line 5—5 of Fig. 3.

Fig. 6 is a view substantially on the scale of Fig. 1 showing one of the two parts which comprise the casing of the device.

Fig. 7 is a perspective view representing one of the two like operating parts of the register.

Fig. 8 is a view representing the ink ribbon and its support.

The improved pocket register, as illustrated herein, is designed to take care of two different kinds of transactions. For example, it may be designed to take care of a cash transaction on one side and charge transaction on the other side. Again, it may be designed to take care of a charge or paid transaction on one side and a C. O. D. transaction on the other side. It may also be designed for other transactions similarly associated in pairs, depending upon the particular salesman who is to use it, and the nature of the business.

Thus the present embodiment of the invention, as illustrated herein, includes two separate and distinct register devices, one of

which is accessible from one side of the pocket register, and the other of which is accessible from the reverse side, and as shown, is located at the opposite end of the register.

- 5 Referring now to that embodiment of the invention illustrated in the drawings:—10, 10 indicate two opposed, flanged plates which provide an inclosing casing for the register, made of separable parts. The said 10 plates are made of a length and width and with a depth of flange such that when assembled, the casing formed is of pocket size and may be conveniently held in one hand for use. Said plates are locked together by 15 means of locking devices 11, 11 placed preferably on opposite sides of the casing and adapted to be locked or unlocked by means of a key or keys held as usual in the hands of the cashier or of another person in authority.

Within the casing are located two register devices indicated respectively at 12 and 13. As each of the register devices as shown herein, are of like construction, a description 25 of one will suffice for both.

The register device 12, is shown in perspective in Fig. 7. It has a frame 14^x comprising side bearing plates 14, 14, spaced apart a distance equal to the space between 30 the flanges of the plates 10, 10, and an end plate 15. A top plate or platen 16, extending transversely between the plates, is supported in any convenient fashion on the top edge of said plates. As shown, said platen 35 has locking extensions 16^a which engage in notches 17 in the top edges of the side plates 14. Supply rolls 18, 19 are rotatively supported by the side bearing plates 14, 14 in a position below the platen 16. One of said 40 rolls, namely: the roll 18, is a check strip supply roll, and the other, 19, is a record strip supply roll.

Near the forward end of the frame 14^x and below the platen 16, is located a record 45 strip rewind roll 20. Forward of that are feed rolls 21, 22, between which are fed the check strip and record strip, the first being fed forward beyond the register to be torn off as will be presently described, and the 50 other being fed between said rolls and then back about the lower roll 22 and thence to the rewind roll 20.

At the rear end of the platen 16 are placed idle rolls 18^a, 19^a, with their top surfaces in 55 the plane of said platen. About said rolls are threaded respectively, the check strip 18^b and the record strip 19^b to bring them in position upon the top of the platen. Between the two strips is located a carbon or ink 60 ribbon 23. This ribbon is attached at its rear end to a rod 24 which has looped or hooked ends 25 adapted to be engaged about the spindle of the idle roll 18^a about which the check strip is fed. Said ribbon is of a 65 length substantially equal to the length of

the platen and is free at its forward end, the feed of the two strips being relied upon to hold the ribbon in smooth, flat engagement between the two strips.

Each of the spindles upon which the check 70 strip roll 18, the record strip roll 19 and the rewind roll 20 are wound, are constructed and mounted in the side bearing plates 14, 14 of the frame 14^x in the same manner. Each comprises a mandrel 26, upon which 75 the paper roll is placed, and spring controlled, expanding spindle parts 27, 27 adapted for engagement in bearing openings 28, 28 in the side plates 14. By pressing the spindle parts 27, 27, inwardly, each spindle 80 with its mandrel may be withdrawn from the frame 14^x when it is necessary to replace the record and check strip rolls, and to facilitate their withdrawal from the frame and also their re-insertion into place, guide channels 29, 29 of a familiar kind are provided on the inside walls of the side plates of the frame.

The feed rolls 21, 22 are rotatively mounted in any suitable manner in the side bearing 90 plates 14, 14 and are provided adjacent one of said plates with interengaging spur gears 21^a, 22^a respectively. A gear 30 is fixed on one of the spindle parts 27 of the record strip rewind roll 20 in the plane of the gears 95 21^a, 22^a. In the plane of the several gears 21^a, 22^a and 30, is placed an operating gear 31 which engages the gears 21^a and the gear 30. Said gear 31 is mounted on a stud 32 rotatively mounted in the adjacent plate 100 14 and prolonged beyond the same, which has attached to it a knurled operating head 33, by means of which it may be rotated.

The bearing side plates 14 of the frame 14^x are made somewhat deeper at their front 105 ends to provide bearings for the top feed roll 21, substantially in or somewhat above the plane of the platen 16. The end plate 15 has a horizontal flange or rear extension 34 which lies above and provides a top closure 110 for the gears heretofore mentioned. The spindles of the feed rolls 21, 22 and of the idle, guide rolls 18^a, 19^a, are nonremovably mounted in the side plates 14.

In the end plate 15 of the frame 14^x, is 115 formed a slot 36 through which the check strip is to be fed. A plate 37 with its bottom edge in line with the top edge of said slot 36, is fixed to the end plate 15 to reinforce and brace said plate adjacent the slot 120 and also to provide a stiff, cutting edge against which the check strip may be torn when detaching a check to give to the purchaser. To prevent back ratcheting of the gears, a spring controlled or resilient pawl 125 38 is provided for engagement with the operating gear 31. Said pawl is attached to the adjacent plate 14 of the frame 14^x. A tension device is provided for properly holding 130 the two feed rolls in engagement with

the superimposed record and check strips. As shown, this consists of a transversely extending, spring bar 39 (see Figs. 4 and 5) having upwardly extending arms 39^a with 5 rounded notches for engagement with the ends of the spindle of the bottom feed roll 22, and of a finger lever 40 pivoted against the inside face of the end plate 15 near the middle of said plate and below said bar 39, 10 which has an arm 41 for engagement with the bottom end of said bar. Manifestly, by swinging the lever, the upwardly extending arms of the bar may be caused to induce pressure as desired between the two feed 15 rolls.—the frictional engagement of a screw 40^a which provides the pivotal support for the lever, acting to hold the lever in any position in which it is placed. In order to facilitate this operation of the tension device, 20 the spindle bearing ends of the lower feed roll 22 are mounted in vertically elongated slots 22^b in each side plate 14.

Each register device, as thus described, is complete in itself and may be removed from 25 or inserted into the casing as an entirety. Each plate 10 is provided with a slot 42 near one end extending transversely across its face and being of an extent to disclose the 30 part of the check strip which lies above the associated platen 16.

Beyond the slot 42, said plate is raised as indicated at 43, and the side and end flanges of the plate adjacent thereto, are deepened to accommodate the difference in depth at 35 the end of the frame of the register device, as clearly appears in Figs. 1 and 6. One side flange 10^a also of each plate 10 is cut to receive the projecting part of the operating stud 32, so that the operating head 33 may 40 extend beyond the outer surface of the flange 10^a.

In assembling the pocket register, one register device (after it has been loaded with the record and check strip supply rolls and 45 after the strips have been fed over the platen by the feed rolls and the record strip has been partially wound upon the rewind roll 20, all in a familiar manner), is placed within the side and end flanges of one plate 10 50 with its platen 16 below the associated opening 42 in said plate 10 and with the deeper part of the frame 14^x engaged under the raised part 43 of the plate 10. The other register device is, in a similar manner, 55 placed in the other plate 10, and the two plates brought together, as shown in Figs. 1 and 2, with the platens of the register devices on reverse sides and directed in opposite directions,—the register devices each 60 being half the length of the plates so that they will abut against each other at their adjacent ends. The two plates are then locked together by means of the locking devices 11, 11 heretofore referred to.

65 When thus assembled, and locked, there

will be left, in the embodiment of the invention shown, in which the flanges of the plates 10, 10 are not quite as deep as the side plates 14, 14 of the register frames 14^x, slots 44 at the ends of the casing which are in line 70 with the slots 36 in the end plates 15 of the register frames 14^x. Through said slots the check strips are threaded and the pocket register is then in condition for use.

The operation of the improved pocket 75 register will be manifest from the foregoing description. Its immediate advantages may be illustrated by particular reference to one of the examples of its use referred to in the preamble of the specification. 80

Suppose it provided with record strips, one on one side for cash sales and one on the other side for charge sales, and the check strips printed for use in connection with a 85 gasoline service station.

An automobilist drives up to the station for gas and the salesman, when told the amount of gas required, has it drawn into the tank of the machine. He then proceeds to the driver and either from previous 90 knowledge or by question, learns whether the purchase is to be a cash or charge account. In either case, having his pocket sales register in hand, which he has in the meantime withdrawn from his pocket, he 95 enters the number of gallons bought and the cost of the same on the charge side of the register or on the cash side, and in the latter case, by the time the driver has his cash ready to hand him, he has entered the sale and by 100 rotating the proper knurled head 33, withdrawn and torn off the receipt check to hand to the driver in return for the cash received.

In this way, he has necessarily produced a 105 record of the sale which is unchangeably recorded in the register and which shows the amount received and the number of gallons purchased whether the driver has retained the receipt himself or has torn it up and thrown it away. The same result, namely 110 an unchangeable record in the register, is brought about in the case of a charge sale, where the driver is more apt to insist upon and retain the receipt for the amount bought. 115

It will be apparent that the record in the register will be an absolute check on whatever is done by the salesman in the way of giving or not giving receipts, since there must be in the register for each length of 120 check strip to be issued, a corresponding length of record strip to be accounted for by the salesman. Thus whether or not he enters the sale and issues a check or checks, a record to be accounted for by him is retained in 125 the register.

While in describing my invention, I have referred to many details of mechanical construction and arrangement of parts, it is to be understood that the invention is in no 130

way limited thereto except as may be pointed out in the appended claims.

I claim as my invention:

1. A pocket sales register comprising a casing including top and bottom flanged plates, one of which has a writing opening therein, a register unit removably secured in said casing and embraced by the flanges of said plates, said register unit including a platen arranged beneath said writing opening and containing a support for a check strip supply and a support for a record strip supply, which check strip and record strip are adapted to be fed over the platen in superposed relation, said unit also containing a transfer means between the check strip and the record strip below said writing opening, and means within the register unit and operable from without the casing for feeding the check strip outwardly from the casing and for storing up the record strip within the register unit.

2. A pocket sales register comprising a flat, shallow casing including a plurality of parts, means for locking said parts together, two register units placed end to end in said casing, each having a platen and containing supporting means for a check strip and for a record strip, and an interposed transfer means between said check strip and said record strip, the casing being provided with a writing opening for each platen, and means associated with each register unit and operable from the outside of the casing for feeding the check strip of each register unit outwardly from the casing.

3. A pocket sales register comprising a casing including top and bottom, similar, flanged plates and two register units arranged end to end within said casing and embraced by the flanges of said plates, each register unit having a platen and the casing having writing openings corresponding to said platens, each register unit containing supporting means for a check strip and a record strip, and an interposed transfer means between said check strip and record strip, and means associated with each register unit and operable from the outside of the casing for feeding the check strip of each register unit outwardly from the casing.

4. A pocket sales register comprising a casing including oppositely disposed, flanged plates, each having a writing opening therein, one at one end of the casing and the other at the opposite end of the casing, two register units placed end to end in said casing and embraced by the flanges of said plates, each containing a support for a check strip and a support for a record strip, and an interposed transfer means between the two, and means associated with each register unit and operable from the outside of the

casing for feeding the check strip of each register unit outwardly from the casing.

5. In a device of the kind described, a register unit comprising a U-shaped frame, open at top and bottom and provided with a slot in its transverse end wall, a platen parallel to said U-shaped frame, idle rolls 70 rotatively mounted in the side members of said U-shaped frame, at the rear end of said platen, a supporting roll for a record strip and a supporting roll for a check strip, each 75 removably mounted in said side members, the record strip and check strip being arranged to unroll toward said idle rolls and over said platen, feed rolls mounted in said side frame members in advance of said platen and to the rear of the opening in the 80 transverse member thereof, a rewind roll for the record strip removably mounted in said side member back of said feed rolls, and gearing and operating means for rotating said feed rolls and said rewind rolls.

6. In a register of the kind described, a register unit comprising a frame including parallel side members and a slotted, transverse end member, a platen connecting the parallel side members of the frame at their top edges, said platen terminating at one end near said transverse end number, idle rolls, journaled in the side members of the frame at the other end of the platen, a supporting roll for a record strip, and a supporting roll for a check strip, removably journaled in said side members of the frame, beneath the platen, the record strip and the check strip being arranged to unroll rearwardly and about an associated idle roll and then over said platen in superposed relation, attaching means for a transfer member adapted to be interposed between the record strip and the check strip above the platen, a rewind roll removably journaled in the 95 said side members of the frame below the said first mentioned end of the platen, a pair of feed rolls journaled in the side members of the frame, between the said first mentioned end of the platen and the slotted, 100 transverse end member of the frame, and gearing connecting the feed rolls together and connecting said feed rolls with the rewind roll, said gearing being constructed to feed the record strip through the slot in the 105 end member of the frame and to wind up the record strip on the record strip rewind roll.

In testimony that I claim the foregoing as my invention, I affix my signature in the presence of two witnesses, this 10th day of January, A. D. 1918.

JOSHUA LINCOLN MORRIS.
